DESIGN FOR A PLASTIC FABRIC

Harry Morris, Chicago, Ill.

Application April 19, 1946, Serial No. 128,752

Term of patent 14 years

(Cl. D87—3)

To all whom it may concern:

Be it known that I, Harry Morris, a citizen of the United States, residing in Chicago, in the county of Cook and State of Illinois, have invented a new, original, and ornamental Design for a Plastic Fabric, of which the following is a specification, reference being had to the accompanying drawing, forming part thereof.

Fig. 1 is a plan view of a plastic fabric, showing my design, and

Fig. 2 is an edge view thereof on an enlarged scale.

Fig. 3 illustrates the cross sectional appearance of the fabric on lines 3—3 of Fig. 1.

Fig. 4 illustrates the cross sectional appearance of the fabric on lines 4—4 of Fig. 1.

I claim:

The ornamental design for a plastic fabric, substantially as shown.

HARRY MORRIS.
